DESIGN FOR A SHOE

Frank Faleck, New York, N. Y., assignor to Ansonia De Luxe Shops, Inc., New York, N. Y., a corporation of New York

Application April 18, 1936, Serial No. 62,204

Term of patent 3½ years

To all whom it may concern:

Be it known that I, Frank Faleck, a citizen of the United States of America, residing in city of New York, county of New York, and State of New York, have invented a new, original, and ornamental Design for a Shoe, of which the following is a specification, reference being had to the accompanying drawing, forming part thereof.

Fig. 1 is a plan view of a shoe showing my new design.

Fig. 2 is a side elevational view of a shoe as shown in Fig. 1.

Fig. 3 is a rear view of a shoe as shown in Fig. 1.

I claim:

The ornamental design for a shoe substantially as shown.

FRANK FALECK.
